UNITED STATES PATENT OFFICE.

GUILFORD L. SPENCER, OF TINGUARO, MATANZAS, AND VIRGIL E. METCALFE, OF DELICIAS, ORIENTE, CUBA; EMMA F. SPENCER, EXECUTRIX OF SAID GUILFORD L. SPENCER, DECEASED, ASSIGNOR TO EMMA F. SPENCER.

CONTROL SYSTEM.

Application filed October 22, 1924. Serial No. 745,241.

This invention relates broadly to the method of and apparatus for the control of centrifugal separators, and has for its main object the provision of means for measuring, 5 limiting, or measuring and limiting the application of centrifugal force to such machines. More particularly, this invention relates to the control of centrifugal separators used in purging the sugars of the 10 mother liquor, and to the provision of means for applying, preferably automatically, a wash of water or other suitable substance to the purged sugars at the proper time and in the proper quantity.

15 In the present practice of operating centrifugal machines, the operator must judge as to the proper time to stop the machine and discharge the purged substance, and he judges by the appearance of the substance, 20 usually, and also is influenced by the time element. Obviously, this method of controlling the operation of the centrifugals is highly inaccurate, and this is especially true because of the short time consumed by the 25 cycle of necessary operations. For example, in treating a high grade sugar magma or massacute of moderate density in a modern centrifugal separator of the self-discharging or bottomless type, the full cycle of operations 30 may not consume one hundred seconds. It would require about thirty seconds for starting, accelerating and charging the centrifugal basket with magma, leaving seventy seconds for purging the sugar, 35 switching off the current, applying the brakes and stopping the machine. Of this period of seventy seconds probable forty to fifty seconds constitute the period during 40 which the machine is exerting full centrifugal force. With such a short cycle of operation, it is apparent that the operator must be very skillful as a small fraction of time incorrectly estimated over or under the time necessary for the proper treatment of the 45 magma will result in improperly treated sugar that will have unsatisfactory storage qualities and perhaps other unsatisfactory characteristics. Further, if the centrifugal machine is allowed to operate too long, there 50 results a wall of sugar so hard that it must be broken down with a paddle and consequently time and machine capacity is lost. It is obvious that the present method is high-

ly disadvantageous and that it is practically very difficult, if not impossible, to obtain a 55 purged product of even quality and proper character. The object of this invention, as broadly stated, is to obviate as far as possible the error usual when human judgment is exercised and provide an automatic control. 60

With the above main object in view, this invention provides electrically operated devices which measure and limit the application of centrifugal force to the material 65 treated so that when the machine is started it will run exactly for that length of time during which just the right amount of energy having a centrifugal force factor will be applied to yield a product of the proper 70 character. When such amount of energy has been applied, a wash is automatically and effectively applied to the material, and the machine is automatically stopped at the proper moment. While this invention contemplates the automatic operation of a control means for the purpose stated, there is also contemplated a manual control following certain indications on a device provided to indicate just when the manual operations 75 are to take place, this manual control being alternative to the automatic control. The invention also contemplates certain provisions for adjustments to meet practical operating conditions as may be required. 80

85 For a complete understanding of the invention reference is to be had to the following detailed description and to the accompanying drawings forming a part of this specification. 90

In the drawings;

Fig. 1 is a diagrammatic view of the apparatus constituting an embodiment of the invention;

Fig. 2 is a plan view of the energy measuring and limiting device constituting an important feature of this invention; 95

Fig. 3 is a sectional view on the line 3—3 of Fig. 2;

Fig. 4 is a side elevational view of the 100 measuring and limiting device;

Fig. 5 is a diagrammatic view of the electro magnets used in the measuring device;

Fig. 6 is a diagrammatic view of a modified measuring device; and Fig. 7 is a diagrammatic view of a master control. 105

Referring to the drawings in detail, and more particularly to Fig. 1, there is provided in connection with the motor M which drives the centrifugal, the shaft C of which is shown the usual brake B. This driving and brake arrangement is well known and is shown conventionally as a detailed showing is not necessary.

A small alternating current generator G is associated with the centrifugal shaft C and is driven thereby through any suitable driving connection, preferably by the associated gears 11 and 12. The energy at unity power factor of the generator G is directly proportional to the centrifugal effect of the centrifugal separator so that by measuring the energy output of the generator G the total centrifugal effect on the sugar or other substance in the separator is measured. The energy output of this generator can be measured by a watthour meter which is shown in Fig. 1 and represented by the reference character 13. This watthour meter is shown in a modified arrangement in Fig. 7 where the meter is designated by the reference character 13'. The meter shown by Fig. 1, generally, and by Figs. 2 to 5, in detail is a specially designed device and constitutes not only a meter but an energy limiting device as will hereinafter more fully appear. It is apparent that since the meter measures the energy output of the generator G which is proportional to the centrifugal effect of the separator, the meter could be calibrated as shown by Fig. 7 so that the operator could stop the centrifugal when the meter gave the proper indication. It could also be marked so that the operator would apply the wash when the sugar had attained a certain dryness, and the meter would also indicate when the separator should be stopped. However, instead of this manual control following indications by the meter, it is proposed to control the centrifugal machines automatically in response to the energy output of the generator G.

As is already apparent from the foregoing discussion, the meter 13 which may preferably be termed an energy integrating device is a very important feature of this invention. Any generator and any watthour meter that would measure the generator output at unity power factor would be satisfactory, and while Fig. 1 shows a two phase generator and a special type of meter or energy integrator shown in detail by Figs. 2 to 5, as will be hereinafter described, the showing is to be considered as general and not specific only to this special type of generator and integrator.

A meter of the induction watthour type must have two sources of magnetic flux, one above and one below the meter disk, if accurate indications of energy at all power factors are to be given. These two sources

of magnetic flux must be mechanically displaced by ninety "electrical space" degrees and the two magnetic fluxes must differ in time phase by an angle whose cosine is equal to the power factor. In this control system, the centrifugal effect is proportional to the square of the speed of the centrifugal separator. An electric generator with a given field excitation generates a voltage directly proportional to the speed of the generator. In a two phase generator as shown by Fig. 1, there are two equal voltages generated in two separate windings, these voltages being ninety degrees out of phase. A meter having two separate windings of equal resistance and equal inductance furnishing excitation to two sources of magnetic flux mechanically displaced by ninety degrees will measure the square of the voltage of the generator and integrate this squared voltage quantity for time and thus give a correct indication of the centrifugal effect.

In Fig. 1, the two phase generator G has its field excited from a constant D. C. source 14 and this generator furnishes excitation to the windings 15' and 16 of the meter or integrator 13. Referring to Fig. 2, this integrator comprises two electromagnets 17 and 18 and a disk 19 having associated therewith the usual brake magnet 20. The mechanical and electrical arrangement of these magnets 17 and 18 are clearly shown by Fig. 5, and it will be seen that winding 15' which is excited by one phase of the generator G furnishes one source of flux and that winding 16 which is excited by the other phase of the generator furnishes the other source of flux, and that the two sources of flux are displaced mechanically by ninety degrees. This combination of two phase meter and two phase generator will be accurate and independent of frequency, as the meter is the sole load of the generator and each meter winding has equal resistance and equal inductance and therefore the current in each phase will lag behind its voltage by the same amount so that the fluxes from the two sources are ninety degrees apart regardless of frequency. The torque acting on the disk 19 will therefore be solely and directly proportional to the square of the voltage of the two phase generator G, which is proportional to the square of the speed of the centrifugal separator.

The disk 19 is secured to a spindle 21 which is journalled in bearings 22 and 23 secured in lower and upper brackets 24 and 25, respectively. These brackets are associated as shown with the magnet holding frames 26 and 27. A counter spindle 28 is driven at reduced speed by the spindle 21 through the reduction gears 29 and 30. The spindle 28 is journalled at its lower end in a bearing 31 supported from the bracket 25 and its upper end in the upper end of the

hollow insulation sleeve 32 which is also secured to the bracket 25. On this sleeve 32 are adjustably mounted rings 33, 34, 35 and 36. These rings may be mounted on the sleeve 32 in any suitable manner and may frictionally embrace this sleeve so that when any particular ring is moved circumferentially thereof it will remain in its adjusted position until manually reset. To the spindle 28 is secured what may be termed a power hand P. To the ring 33 is fixed an arm 37 which acts as a stop for the hand P, and to the rings 34, 35, and 36 are secured the arms S, SW, and W, respectively. In Fig. 1 there is a conventional showing of the rings and the associated arms, the same reference characters being used. It will thus be seen that as the spindle 21 is rotated motion is imparted to the counter spindle 28 which actuates arm P which makes contact at certain times with arms W, SW, and S.

Referring now to Fig. 1 it will be seen that the contact of arm P with contact arms W, SW, and S controls certain electrical circuits and by referring to the diagram of connections shown by Fig. 1, the operation of the entire system will now be explained. Upon pressing the start button 38, the stop button 39 closing the circuit, a circuit is completed through magnet 40 which being energized closes the main three pole switch 41 and also closes all the contacts, m^1 , m^2 , and m^3 of the main relay MR. When the main switch 41 is closed the driving motor M starts and at the same time the brake solenoid 42 is energized, releasing the brake band and permitting the centrifugal separator to accelerate to speed. As the shaft C of the centrifugal separator rotates, the generator G delivers energy to the meter or energy integrator 13, the disk 19 being thereby rotated to drive the spindles 21 and 28, the spindle 28 actuating the arm P. As the arm P moves it makes contact with the contact arm W and thereby completes a circuit across the control mains 43 which supply current preferably at 110 volts and 60 cycles, this circuit being made through relay contacts a^2 , b^2 and m^1 , all contacts of main relay MR being closed, and through solenoid A of relay AR. When solenoid A is thus energized, contact is made at a^1 , a^3 , and a^4 . The contact at a^1 now completes the circuit that at first went through P and W, and contact at a^2 being now broken, the arm P may move from the arm W without any arcing since the circuit through these contact members has already been broken. When relay contact a^3 is closed, the valve solenoid 44 is energized to attract the valve operating arm 45 against the closing spring 46 to open the valve 47 which permits washing liquid to flow from the pipe 48 which will be properly positioned in the centrifugal basket as is ob-

vious. The solenoid 44 remains energized during the travel of the arm P from the contact W to the contact SW. When the arm P makes contact with SW, a circuit across the line 43 is completed through the relay contacts b^3 , solenoid B of relay BR, and relay contacts a^4 of relay AR, a^4 being closed at this time, whereupon relay contacts b^2 and b^3 open, and b^1 closes, the opening of b^3 and closing of b^1 puts the solenoid B in a circuit independent of SW so that no arcing will occur when the arm P and contact SW separate. As soon as b^2 opens there is no circuit through solenoid A and relay contacts of AR consequently open, except a^2 which closes. As a^2 opens there is no circuit through solenoid B, and therefore contact b^1 opens and contacts b^2 and b^3 close. When contact a^3 opens, valve solenoid 44 is de-energized and spring 46 closes the valve 47. As contact arm P continues to move, it makes contact with contact arm S and thereby completes a circuit through solenoid C of relay CR across the line 43. When solenoid C is energized, contacts c^1 open to thereby open the circuit through the solenoid 40 and the main switch 41 consequently opens and likewise the relay contacts of main relay MR also open, and the brake solenoid 42 being de-energized, permits the brake spring to be applied to the brake band which quickly brings the centrifugal machine to a stop.

While the centrifugal machine is being stopped, the main contact arm P is returned to zero position against the fixed stop 37 by the preferred means shown by Fig. 3. This arm returning means is preferably a weight w connected to the spindle 21 by a cord 49 which may be secured to a pulley 50 secured to the spindle 21, this cord passing over an idler pulley 51. The weight w is just heavy enough to give sufficient torque to effect the return of the arm P to the starting position in the time allowed for the centrifugal machine to stop. The meter may be compensated for the counter torque of the weight in the same way that the retarding effect of friction is compensated for in watthour meters and for induction meters compensation could be made following the principle of the shaded pole.

If a battery of centrifugal machines is to be controlled, it might be desirable to provide a master control arrangement such, for example, as is shown diagrammatically by Fig. 6. Generators G¹ and G² are shown as single phase generators and are supplied by current for their field excitation from a common source 14', the strength of this field excitation current being regulated by the rheostat R¹.

In Fig. 7 there is shown a modification of the combination of the small generator on the centrifugal shaft and the integrat-

ing device. The generator G^1 will be driven as shown by Fig. 1 and will supply current to a non-inductive load L which may be varied. The meter or energy integrator 13' will measure the output of the generator G^1 and a conventional watthour meter having a spindle 28' which may be arranged to be driven by the spindle of the watthour meter, such as spindle 21 as shown by Fig. 13', this spindle 28' actuating a hand P' which may travel over a scale S to indicate to an operator when to perform each operation in the cycle of operations as previously described. It will be understood that the hand P' could, instead of moving over a scale S , or besides moving over this scale, be arranged to make the contacts as made by the hand P as described in connection with Figs. 1 to 5. It is apparent that the use of a small generator and an integrating meter or energy integrating device is an important and the essential part of the system of control, but the type of generator and the type of integrator is relatively unimportant as the method and apparatus may include generators and integrators of the alternating or direct current type.

Reverting to the master control for a battery of centrifugal machines, its operation may be readily understood considering the showings of Figs. 6 and 7 together. In Fig. 7, the generator G^1 corresponds to the generator G^1 in Fig. 6. When it is necessary or desirable to change the length of the cycle of operations on a battery of controlled centrifugal machines, each of which has been individually set by means of the individual adjustable load resistance L to give the desired product, the master control arrangement shown by Fig. 6 may be used. By adjusting the rheostat R^1 , the field excitation of all the generators G^1 , G^2 , etc., may be varied to vary the generated voltage to thereby vary the time required for the hand P or P' to move the required distance over the scale S or to make the required contacts with contact arms W , SW , and S . This master control in conjunction with the individual controls gives a highly flexible control that adapts the system for use with centrifugal machines treating various magmas.

For the sake of clearness and in order to disclose the invention so that the same could be readily understood, specific devices and arrangements have been described and illustrated. It is to be understood, however, that this invention is not limited to the specific means disclosed but may be embodied in other ways that will suggest themselves, in view of this broad disclosure, to persons skilled in the art. It is believed that this invention is broadly new and it is desired to claim it as such so that all such changes as come within the scope of the

appended claims are to be considered as part of this invention.

Having thus described our invention, what we claim and desire to secure by Letters Patent of the United States is:—

1. In combination, a rotary machine, energy responsive means for controlling the operation of said machine, and means for furnishing energy to said energy responsive means in proportion to the energy developed by said rotary machine. 75

2. In a control system for rotary machines, means for generating energy in proportion to the energy of the rotary machine, and means responsive to the energy of said generating means for controlling the operation of the rotary machine. 80

3. In a control system for centrifugal separators, an electric generator associated with the centrifugal separator and delivering energy in proportion to the energy developed by the centrifugal separator, and means responsive to said electric generator energy for controlling the operation of the centrifugal separator. 85

4. In a control system, a driven machine, means for generating energy in direct proportion to the energy generated by said driven machine, and devices successively responsive to said generated energy. 90

5. In combination with the shaft of a rotary machine, an electric motor for driving said shaft, an electric generator associated with said shaft, means for receiving and integrating the energy delivered by said generator, and means associated with said integrating means for stopping said electric motor. 100

6. In a control system for centrifugal machines, an electric generator associated with a centrifugal machine and delivering energy in proportion to the energy developed by the centrifugal machine, and means for integrating the electrical energy. 105

7. In combination with a driven machine, means for generating and delivering energy in proportion to the energy developed by the machine, and means responsive to said generated energy for stopping said machine. 110

8. In combination, a rotary machine, a two phase electrical generator driven thereby, means for integrating the energy of said generator, comprising two separate windings excited separately from the two phases of the generator, a disk actuated by the current generated therein by the action of the fluxes having said windings as sources, and means actuated by said disk for controlling the operation of said rotary machine. 115

9. In a control system, a driven machine, means for generating energy in direct proportion to the energy generated by said driven machine, and means responsive to said generated energy for stopping said driven machine. 125

70

100

105

110

120

130

10. The method of controlling the operation of a rotary machine comprising furnishing energy to an energy responsive device in proportion to the energy developed by the machine and stopping said machine after said energy responsive device has consumed a predetermined amount of energy.

11. The combination with a rotary machine, of means for generating energy in proportion to the square of the velocity of said rotating machine, and means actuated

by the energy of said generating means for stopping said machine.

12. The combination with a rotary machine, of a two phase generator driven thereby, and means actuated in proportion to the energy of said generator for controlling the operation of said machine. 15

In testimony whereof, we hereunto affix our signatures.

GUILFORD L. SPENCER.
VIRGIL E. METCALFE.
